ELASTIC SMOCKING

Joseph L. Selinger, New York, N. Y.

Application March 8, 1937, Serial No. 129,591

1 Claim. (Cl. 2—278)

This invention relates to new and useful improvements in smocking material and has more particular reference to elastic smocking.

The invention has for an object the construction of smocking material which is characterized by cloth material having on one side a plurality of gathered adjacent portions in adjacent lines with the ends of the gathered portions of adjacent lines straddling each other, and an arrangement for resiliently maintaining the gathered portions in formation.

Still further the invention proposes the provision of a plurality of parallel lines of elastic cords on the other side of said cloth material and secured thereon with lines of zigzag stitches for resiliently maintaining said gathered effect.

Still further the invention contemplates a method by which the elastic smocking may be readily constructed.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

Fig. 1 is a fragmentary front elevational view of a piece of elastic smocking constructed according to this invention.

Fig. 2 is a rear elevational view of Fig. 1.

Fig. 3 is a sectional view taken on the line 3—3 of Fig. 1.

Fig. 4 is a view similar to Fig. 1 but illustrating the material in fully stretched position.

Fig. 5 is a view similar to Fig. 2 but illustrating the material in fully stretched position.

Fig. 6 is a fragmentary view similar to Fig. 5 but illustrating a modification.

The elastic smocking, according to this invention, comprises cloth material 10 having on one side 10^a a plurality of gathered adjacent portions 11 arranged in adjacent lines with the ends of the gathered portions of adjacent lines straddling each other. Parallel lines of elastic cords 12 are secured on the other side 10^b of the cloth material 10 by zigzag stitches 13. These elastic cords resiliently maintain the gathered effect.

Fig. 4 illustrates the cloth material as viewed in Fig. 1 stretched laterally. When thus stretched the gathered portions 11 will be flattened out and the cloth material 10 will be flat. The only effect now viewable will be the zigzag stitches 13. The dot and dash lines 11' schematically indicate the portions of the sheet material which will be gathered when the cloth is released. Fig. 2 shows the rear view of the gathered material.

It should be noted that the lines of elastic cords 12 are arranged in groups. Each group extends across the full width of the zigzag stitches 13. These groups are spaced and it is the material between the spaced groups that will be gathered. The gathering 11 will be produced by the material between opposed apexes of adjacent lines of zigzag stitches as clearly indicated in Fig. 4.

The rear view shown in Fig. 5 represents merely a flat sheet of material 10 upon which there are parallel lines of elastic cords 12 held by zigzag stitches 13.

In Fig. 6 a modification of the invention has been disclosed in which scallop shaped zigzag stitches 13' are used to hold down the parallel groups of cords 12' upon the sheet material 10'. The dot and dash lines 11'' schematically indicate the portions of the material 10' which will become gathered when the cloth material 10' is released.

The method of manufacturing the elastic smocking consists in stretching parallel lines of elastics 12 across one side of cloth material and then sewing the elastics on the cloth material with parallel lines of zigzag stitches. When the cloth material and elastics are released the elastics will contract the cloth material and form the gathered portions. The gathered portions must come out on the front side of the material since the elastics tend to assume straight line positions and so force out the gathering on the front side.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

Elastic smocking material formed of cloth material and a plurality of spaced, substantially parallel series of elastic cords continuously secured thereto by zigzag seams of relatively tight stitching, a plurality of stitches in each of the legs of said seams, said elastic cords being secured to said cloth while said cords are in a stretched condition whereby to form gatherings in said material when said cords assume a normally relaxed condition, said cords being separated one from another by said stitches, the legs of said seams defining the ends of said gatherings.

JOSEPH L. SELINGER.
